UNITED STATES PATENT OFFICE

WILLIAM H. CARSON, OF NEW ROCKFORD, NORTH DAKOTA

DESIGN FOR A ROAD SIGN

Application filed April 2, 1930. Serial No. 35,110. Term of patent 7 years.

To all whom it may concern:

Be it known that I, WILLIAM H. CARSON, a citizen of the United States, residing at New Rockford, in the county of Eddy and State of North Dakota, have invented a new, original, and ornamental Design for Road Sign, of which the following is a specification, reference being had to the accompanying drawings, forming part thereof, wherein:

Fig. 1 is a perspective view of a road sign showing my design;

Fig. 2 is an end elevation of the same;
Fig. 3 is a front elevation of the same;
and

Fig. 4 is a top plan view of the same.

What I claim is:

The ornamental design for a road sign substantially as shown.

WILLIAM H. CARSON.
